(57) **CLAIM**

I claim the ornamental design for a deep fryer, as shown and described.

DESCRIPTION

FIG. 1 is a front view of the deep fryer showing my new design;

FIG. 2 is a rear view of the deep fryer depicted in FIG. 1; FIG. 3 is a right, side view of the deep fryer depicted in FIG. 1;

FIG. 4 is a left, side view of the deep fryer depicted in FIG. 1;

FIG. 5 is a top view of the deep fryer depicted in FIG. 1; FIG. 6 is a bottom view of the deep fryer depicted in FIG. 1; and,

FIG. 7 is a top, right perspective view of the deep fryer depicted in FIG. 1.

The broken lines in the drawings illustrate portions of the deep fryer that form no part of the claimed design.
